LAMP BASE

Gilbert P. Hess, 2065 Emporia St.,
Aurora, Colo. 80010

Filed Apr. 3, 1975, Ser. No. 564,611

Term of patent 14 years

Int. Cl. D26—05

U.S. Cl. D48—20 C

FIG. 1

FIG. 2

FIG. 3

FIG. 4

FIG. 5

FIG. 1 is a front elevational view of a lamp base showing my new design;

FIG. 2 is a side elevational view thereof;

FIG. 3 is a rear elevational view thereof;

FIG. 4 is a top plan view thereof; and

FIG. 5 is a bottom view of the lamp base of my design.

I claim:

The ornamental design for a lamp base, as shown.
